UNITED STATES PATENT OFFICE.

ORVILLE EWING AND GEORGE A. HENDERSON, OF DECATUR, ILLINOIS.

DITCHING-MACHINE.

SPECIFICATION forming part of Letters Patent No. 283,735, dated August 28, 1883.

Application filed May 26, 1883. (No model.)

To all whom it may concern:

Be it known that we, ORVILLE EWING and GEORGE A. HENDERSON, citizens of the United States, residing at Decatur, in the county of Macon and State of Illinois, have invented certain new and useful Improvements in Ditching-Machines, of which the following is a specification.

Our improvements relate to that class of ditching-machines which are self-propelling.

The objects of our improvements are, first, to cut the ditch to the required width and depth by means of a vertically-moving spade cutting successive narrow vertical sections, one at each stroke; second, to provide means for elevating and distributing the earth loosened by the spade; third, to provide means whereby a person riding on the machine can regulate the grade of the bottom of the ditch by the aid of targets erected on the field, and a movable sight and stop on the machine; and fourth, to move the machine forward with a regularly intermittent movement.

The accompanying drawings illustrate our invention.

Figure 1 is a side elevation. Fig. 2 is an elevation of the front end with the engine and a portion of the boiler removed. Fig. 3 is a perspective view of the device for shifting belts driving the spade. Fig. 4 is a plan of the same.

Like letters indicate the same parts in all the figures.

A is a rectangular frame, having one end mounted on a pair of traction-wheels, and the other end on a pair of carrying-wheels. A suitable steam boiler and engine are mounted on said frame near the traction-wheels. A pair of vertical parallel ways, *aa*, formed preferably of T-iron, are erected on frame A and suitably braced thereon. The spade *b* is secured to the lower end of the spade-staff *c*, which is jointed at *d* in such a manner that it will bend backward but not forward. The spade-staff is secured near the top to a cross-head, *e*, which fits and moves freely between the ways *aa*. The upper end of the spade-staff is provided with cog-teeth, forming a rack, *f*, the teeth of which intermesh with those of a pinion, *g*, on shaft *h*, which is journaled in bearings secured to the tops of the ways. Shaft *h* carries at one end a pair of loose pulleys, *i j*,

and between them a fast pulley, *k*. Said pulleys are connected by an open belt, *m*, and a cross-belt, *n*, with pulleys *o p* on the main shaft *q*, which is driven by the engine. On the opposite end of shaft *h* is a cone-pulley, *l*, fitted to turn thereon. A clutch, *t*, turns with the shaft and engages pulley *l*, turning it with the shaft when turning in one direction, but slipping over and leaving the pulley stationary when turning in the opposite direction. Shafts *r* and *s*, also secured to the ways, carry the cone-pulley *t* and sprocket-wheels *u v*, and *w*. A sprocket-wheel, *x*, is secured to the axle of the traction-wheels. Sprocket-wheels *u v*, and *x* are connected by chains *y z*. A belt, *a'*, connects cone-pulleys *l* and *t*. Secured to the outside of one of ways *a* is a rack, *b'*, into which a screw-pinion, *c'*, meshes. Said pinion is mounted in a frame, *d'*, which embraces and slides upon the way *a*. The pinion is revolved by a person riding on the machine turning the hand-wheel *e'*. A sight, *f'*, is attached to or formed upon frame *d'*, for a purpose hereinafter explained. On the front of the cross-head is a sliding bar, *g'*, having its ends bent to form oppositely-inclined planes, one of which strikes a corresponding incline on the sliding frame *d'* as the spade nears the bottom of the ditch, and the other strikes a stop, *h'*, secured to the way *a*, as the spade rises. Said bar *g'* is connected by a rod, *i'*, with a vertical rod, *j'*, which is provided at each end with an arm, *k'*, pivoted at one end to the way *a*. Rod *i'* embraces rod *j'* loosely, so that it may slide up and down thereon. A shifter, *l'*, connected with rod *j*, engages belts *m* and *n*.

The earth is excavated and raised after being cut down by the spade by means of the elevator *m'*, and is conveyed to the rear of the machine by a conveyer, *n'*. Said conveyer is pivoted at *o'* to a frame erected on A, and the elevator is at the top hinged to the frame of said conveyer. The relative position of pivot *o'* is such that the conveyer will be held in position by the weight of the elevator, the lower end of which is provided with a shoe, *s'*, which rests upon and smooths the bottom of the ditch. A platform, *p'*, is provided, on which tiles may be carried, and a workman may stand to lay them in the ditch as it is made. A hopper, *r*, swiveled on the top of post *s'*, receives

the excavated earth as it falls from the conveyer. Said hopper may be set to guide the earth directly to the rear, and thus cover the tiles after they are laid, or to either side of the ditch.

- The operation of our machine is as follows: The ditch is opened by hand to the required depth sufficiently to let the elevator rest on the bottom and be in position for working.
- 10 Sliding stop d' is then adjusted on way a by turning the screw-pinion e' till the spade will move downward very nearly to the bottom of the ditch before sliding bar g' will come in contact with the stop. Two targets are now erected at a considerable distance from the machine on the line of the proposed ditch. Their relative height is such that a straight line drawn through both targets and through sight f' on stop d' will be parallel with the inclination or grade of the ditch-bottom. Stop h' is now set at such a point that the sliding bar g' will come in contact with it when the spade has been raised clear of the surface. The engine is now started, belts m and n being in the positions shown in Fig. 2, n being on the fast pulley and m on the loose one. Shaft h and pinion g are turned, and the spade is forced down till sliding bar g' , coming in contact with stop d' , is moved endwise in an obvious manner, thus moving shifter l' and throwing belt n off the fast pulley k and bringing belt m thereon, thus changing the direction of rotation of shaft p , and raising the spade at the same time clutch r' engages cone-pulley l , and the belt h' and chains y and z being set in motion thereby, the machine is moved slowly forward, the joint d in the spade-staff allowing it to yield to the forward movement of the machine while the spade is below the surface, but 40 falling into line again when clear. When the spade has cleared the surface, sliding bar g' comes in contact with stop h' , and the belts being again shifted thereby, the machine ceases to move forward, clutch r' slipping over the 45 clutch-teeth on pulley l , and the spade again descends. As the work progresses the attend-

ant, riding on the machine, looks frequently through the sight f' and keeps it constantly adjusted in line vertically with the targets, thereby controlling the depth to which the spade penetrates irrespective of the configuration of the surface over which the machine moves. As fast as the earth is cut down by the spade it is raised by the elevator and conveyed to the rear. The weight of the elevator resting on shoe s' crushes any loose particles, and the bottom of the ditch is smoothed by the shoe dragging thereon as the machine moves forward. By turning hopper r in the required direction the excavated earth is deposited in the ditch over the tile-drain or to one side, as may be desired.

We claim as our invention—

1. In a ditching-machine, the combination, with a reciprocating spade and reversing mechanism for operating the same, of a movable stop provided with a sight, a belt-shifter, and intermediate connecting mechanism, whereby the said shifter is operated and the movement of the spade controlled by said stop, substantially as shown and described.

2. In a ditching-machine, the combination, with spade b , spade-staff c , rack f , pinion g , shaft h , and means for rotating said shaft alternately in opposite directions, of clutch r' , pulley l , and means for transmitting motion from said pulley to traction-wheels, partially sustaining the machine, whereby the machine is intermittently moved forward, substantially as shown and described.

3. In a ditching-machine, conveyer n' , pivoted to a support, as shown and described, elevator m' , hinged to said conveyer, and provided with a shoe resting upon and adapted to smooth the bottom of the ditch, all combined substantially as shown and described.

ORVILLE EWING.
GEO. A. HENDERSON.
